IMPEDANCE INCREASES IN CASCADE NETWORK

Curtis V. Hinton, Indianapolis, Ind., assignor to the United States of America as represented by the Secretary of the Navy

Application June 19, 1951, Serial No. 232,439

10 Claims. (Cl. 235—61)

(Granted under Title 35, U. S. Code (1952), sec. 266)

This invention relates to an electrical network adapted for use in a computer. More specifically, it relates to a network of the cascade type.

In analogue computers, mathematical functions are generally represented by resistors which are wound in a manner to present a variation of resistance corresponding to a particular function. To perform certain types of mathematical operations, a plurality of such resistor stages are connected together in cascade with the output of one resistor stage taken across the movable contact thereof, feeding the input of the next resistor stage. The position of the movable contact on one resistor is usually independent of the position of the contact of a related stage. Any variation of the resistor setting of one particular stage should not affect the output of the preceding stage.

The numerous methods used in the prior art to effect this desirable end suffered from the disadvantages that they were not sufficiently effective to prevent some loading error on the previous stage, they required resistors and other components which were impractical or expensive to construct and resulted in appreciable attenuation.

One of the objects of the invention therefore is to provide a novel arrangement of resistors which eliminates the aforesaid disadvantages.

A further object of the invention is to provide a novel and improved arrangement of resistors in cascade which provides the variation of a resistor in one stage from affecting the output of the previous stage where the resistor may be of relatively simple and economical construction.

In a cascade network having a plurality of resistors designated to be varied and to represent a plurality of variable functions, it is desirable to employ compensating resistors so that the variation of a given resistor will truly indicate the variation of the function.

A still further object of the present invention is to provide improvements in a cascade electrical network, whereby the network is made practical and can handle a very wide range of functions upon which computations are to be made. With the present invention the construction and design of computer elements is amplified; there is less need for supplemental equipment; the output is increased by elimination of inherent attenuation; accuracy is increased by the simplification; and in fact, the method employed is theoretically accurate.

A broad feature of the invention is in providing a plurality of cascaded resistor network stages each comprising a variable resistor wound to represent a desired function and a compensating variable resistor connected in series therewith across the input to the stage in a manner that the sum total of the resistance contributed by the function resistor of the stage at any setting thereof plus the parallel resistance combination of the compensating resistor associated therewith and the load of all the succeeding stages always equals the maximum value of the function resistor. The ratio of the maximum value of the function resistor of one stage to that of the preceding stage is made greater than one, so that the

value of the variable resistors of each stage is of reasonable value.

Other objects and many of the attendant advantages of this invention will be readily appreciated as the same becomes better understood by reference to the following detailed description when considered in connection with the accompanying drawings wherein:

Fig. 1 is a diagrammatic view of the cascade electrical network forming the invention of the present invention.

Fig. 2 shows function and compensating resistor cards used when a squared value is used in computation.

Fig. 3 shows the cards for use with a linear value.

Fig. 4 shows the cards for use with a square root.

Fig. 1 shows the electrical network of the present invention in which there are m variable function resistors 10 having maximum values R , RC_1 , RC_1C_2 , $RC_1C_2C_3 \dots R(C_{m-1})!$ and a final or load resistor 11 having a fixed $R(C_m)!$, each of $C_1C_2C_3 \dots C_m$ being some constant that is greater than one. In the above expressions $(C_m)! = (C_1C_2C_3 \dots C_m)$ and $(C_{m-1})! = (C_1C_2C_3 \dots C_{m-1})$. Each of the C 's may be equal to any or all of the other C 's or to none of them, and all of the C 's may be equal. Each of these resistors is greater than the preceding resistor and is in fact a certain C times greater. The effective value of any function resistor is $(1-X)$ times its maximum value, X varying from 1 to 0, and is determined by the position of a shiftable tie or brush 12 extending between the function resistor 10 and its associated compensating resistor 13 and connected in series with the next function resistor R . Each compensating resistor is so calibrated that if the effective value of the function resistor is $R(1-X)$ the effective value of the compensating resistor at that time is

$$\frac{RCX}{C-X}$$

which has a maximum of

$$\frac{RC}{C-1}$$

when $X=1$, the particular C being the ratio of the next function resistor to the present function resistor. However, since each function resistor is a certain C times the preceding function resistor in maximum value, the compensating resistors increase in the same ratio, thus having the values

$$\frac{RC_1}{C_1-1}, \frac{RC_1C_2}{C_2-1}, \frac{RC_1C_2C_3}{C_3-1}, \dots \frac{R(C_m)!}{C_m-1}$$

The final resistor 11 is in series with the tie 12 for the last function resistor 10. The final resistor and all the compensating resistors 13 are in parallel with one another. With the values of the function resistors, their associated compensating resistors and the final resistor as stated, the effect is one of constant loading for each stage function and compensating resistors regardless of the position of the tie 12, that is the value of X , and the resistance or impedance of each stage is a certain C times that of the preceding stage. Thus the function and compensating resistors of stage n and the load resistor 11 impose on stage $n-1$ the following loading according to Ohm's law:

$$\begin{aligned} & R(C_{m-1})!(1-X) + \frac{\frac{R(C_m)!XR(C_m)!}{C_m-X}}{\frac{R(C_m)!X}{C_m-X} + R(C_m)!} = \\ & R(C_{m-1})!(1-X) + \frac{R(C_m)!XR(C_m)!}{R(C_m)!X + RC_m(C_m)! - R(C_m)!X} = \\ & R(C_{m-1})!(1-X) + R(C_{m-1})!X = R(C_{m-1})! \end{aligned} \quad (1)$$

This value can be seen to be constant and independent of X . Similarly, the loading imposed on the stage $n-2$ can be shown to be $R(C_{m-2})!$, and the loading on the first stage is RC_1 .

Proceeding from Expression 1 above, it appears that the voltage drop across any stage is proportional to X and is not affected by the particular values of X at the other stages. Thus the voltage drop across the final resistor or load 11 is proportional to the product of all the X 's.

By studying the above formula, it can be seen that characteristics of the network shown in Figure 1 and just described is that the total resistance which one stage presents to the preceding stage is constant irrespective of the particular setting of the ganged resistors of the stage. The function and compensating resistors of each stage vary in opposite directions, so that when one resistance is zero, the other is contributing its maximum resistance and the sum of the function resistance at any setting plus the net resistance of the compensating resistance is parallel with the net load following it, is always equal to the maximum value of the function resistor. By increasing the load presented by each succeeding stage, the value of the compensating resistors become reasonable. This, of course, results in the maximum value of the function resistor of each stage and its compensating resistor progressively increasing in value. Since the function resistor of each stage reaches its maximum value when the compensating resistor of the same stage is zero, it should be clear that the net resistance of the maximum value of the function resistance of the next stage is equal to the maximum value of the function resistor of the stage including said latter compensating resistor.

As previously stated, each C has some value greater than one. Let it be assumed that the function resistor 10 for the first stage has a maximum value of one or unity, which occurs when $X=0$. Then the maximum value of the compensating resistor 13 of the first stage occurs when $X=1$ and is equal to

$$\frac{C_1}{C_1-1}$$

If each C is arbitrarily made equal to 2, then the compensating resistor has a maximum value of 2. Since the maximum value of the function resistor of the second stage is C times that of the first stage, the former equals 2. Its compensating resistor has a maximum value of 4. Stated in another way, the maximum value of m function resistors are $2^0, 2^1, 2^2, \dots, 2^{m-1}$, and the maximum values of n compensating resistors are $2^1, 2^2, 2^3, \dots, 2^m$. The final or load resistor has a value of 2^m . This makes working out of the resistors for all the stages easier for they are all some power of 2 times the first function resistor.

Each C cannot be less than one, for then the compensating resistor would have a value of

$$\frac{C}{C-1}$$

which would be negative. This cannot be handled with simple circuits.

If $C=1$, then the maximum value of the compensating resistor would be infinity when $X=1$, and some very large and unsatisfactory quantity when X is somewhere near 1. Thus the function resistors must increase in maximum value from stage to stage.

If C is very large, then the function resistors increase tremendously from stage to stage, and compensating resistors, being always larger than their function resistors, since

$$\frac{C}{C-1}$$

is always larger than one, must also increase tremendously.

This would markedly decrease power output at the final resistor 11.

If C approaches one, the function resistors do not increase very fast, but each compensating resistor, being equal to

$$\frac{C}{C-1}$$

becomes very large.

Some intermediate value of C is most desirable which is low enough to prevent the function resistors from becoming too high and high enough to prevent the compensating resistor from becoming too high. The particular value of C for a given stage will depend on the type of function represented by the function resistor 10 of the stage. Suppose that the function and compensating resistors are each formed of wire-wound cards. Practical considerations may determine an upper limit to the ratio of maximum card height to minimum card height, for the maximum may be limited by space, and the minimum by strength of card which must be sufficient to stand up under a winding.

Suppose that in a certain stage where the function resistor is $R(1-X)$ and the ratio of the next function resistor to the instant one is C , $X=V^n$ so that the value of the function resistor is $R(1-V^n)$, and that of the compensating resistor is

$$\frac{RCV^n}{C-V^n}$$

If the function and compensating resistors are wire-wound cards as aforesaid, the areas of the cards will be proportional to the above expressions, and the height of the cards (the dimension in which the wire extends across the cards) will vary in accordance with the derivatives of the expressions with respect to V . Thus the height of the function resistor card will be expressed by $-nRV^{n-1}$, and the height of the compensating resistor card by

$$\frac{RnC^2V^{n-1}}{(C-V^n)^2} \quad (2)$$

Now consideration is to be given to several types of values of n : $n > 1$, $n = 1$, and $0 < n < 1$. As previously stated, X may vary from 0 to 1, and since $V^n = X$ and in all three cases n is positive, V may vary from 0 to 1.

In the case $n > 1$, $n-1$ is positive or greater than 0. C was previously stated as being greater than one. Thus when $V=0$, the above expression for the compensating resistor height equals zero. When $V \leq 1$, the expression must be greater than zero. The condition $V=0$ must be excluded, because the compensating resistor must have some minimum height to have sufficient strength to carry the winding. If a certain maximum ratio of maximum height to minimum height of compensating resistor card is allowable, which under certain conditions is 4, and a certain maximum value of V , say 1, is necessary, then the lower the value of n , the lower the value of C , for a given minimum of V , as is evident from Expression 2. Stated in another way, for a given value of C , the lower the value of n , the lower the minimum value of V . Stated in still another way, for a given value of n , the lower the minimum value of V , the higher the value of C .

For the condition $n=1$, Expression 2 becomes

$$\frac{RC^2}{(C-V)^2}$$

A minimum value of $V=0$ is permissible, since the last expression does not go to zero. If C is made equal to 2, V may vary from 0 to 1 without the aforementioned height ratio exceeding the permitted value of 4. As the minimum value of V goes up from zero, the value of C decreases from two toward one.

For the condition $0 < n < 1$, $n-1$ becomes negative, and V^{n-1} goes up from zero toward infinity, as V goes from one toward zero. If the aforementioned height ratio of 4 is not to be exceeded, the lower the value of n , the

higher the minimum value of V for a given value of C . For a given minimum value of V , the lower the value of n , the higher the value of C .

For the condition $n < 0$, $n-1$ is even more negative than the condition $0 < n < 1$, and V^{n-1} goes up even faster from zero toward infinity as V goes from one toward zero. If a given height ratio is not to be exceeded, the more negative the value of n , the higher the minimum value of V for a given value of C .

In Fig. 2 function and compensating resistors for the condition $n=2$ are illustrated. Thus the value of the function resistor 10 is $R(1-V^2)$. Since the derivative of this expression is $-2RV$, the function resistor comprises a card 14 of uniform slope wound with a wire 15.

The value of the compensating resistor is

$$\frac{RCV^2}{C-V^2}$$

with a derivative of

$$\frac{2RC^2V}{(C-V^2)^2}$$

Thus the compensating resistor 13 comprises a card 16 with a curved slope wound with a wire 17. A straight line is indicated in dash dot on card 16 to show the value of $2RV$, which is what the curved slope of card 16 will approach as a limit as C approaches infinity.

In Fig. 3 the condition $n=1$ is illustrated. Since the function resistor 10 has the value $R(1-V)$, and the derivative is a constant, the function resistor has a card 18 of uniform height wound with wire 19. Since the compensating resistor 13 has the value

$$\frac{RCV}{C-V}$$

and the derivative is

$$\frac{RC^2}{(C-V)^2}$$

the compensating resistor has a card 20 with a curved slope wound with wire 21.

In Fig. 4 the condition $n=0.5$ is illustrated. Here the function resistor 10 has a value $R(1-V^{0.5})$ with a derivative of

$$\frac{-R}{2V^{0.5}}$$

The function resistor has a card 22 with a curved edge, wound with a wire 23. The compensating resistor 13 has the value

$$\frac{RCV^{0.5}}{C-V^{0.5}}$$

with a derivative of

$$\frac{RC^2}{2V^{0.5}(C-V^{0.5})^2}$$

With the value of C chosen between 1 and 3 the compensating resistor has a card 24 wound with a wire 25, card having a curved edge with the minimum height between its ends. With the value of C above 3 the minimum height will be at the end representing $V=1$.

Thus far the discussion has been only of the effect that V has on the compensating resistor card, but the function resistor card will also determine the range of values for V .

In Fig. 2, where the height of the function resistor card 14 is $-2RV$, the ratio of maximum and minimum values of V cannot exceed 4 if the permissible height cannot exceed 4. Thus if V is to go as high as 1, it cannot go below .25.

In Fig. 3 the height of the function resistor card 18 has a uniform height, and so V may vary from 0 to 1 so far as this card is concerned.

In Fig. 4, where the height of the function resistor card 22 is

$$-\frac{R}{2V^{0.5}}$$

the values of V may vary from .0625 to 1, and the permissible height ratio will not exceed 4.

It is also important that the slope of the card be not too great, for otherwise the wire wound thereon may slide unless steps are provided. This may influence the selection of a constant C and the permissible limits of V depending on the value of n being employed.

If the constant C is the same from each function resistor to the next and the ratio of maximum and minimum card heights need not be taken into consideration, the optimum value of the constant is dependent on the number of sets m of function and compensating resistors, as follows:

$$C = \frac{m}{m-1}$$

This is obtained by differentiating the expression for the compensating resistor of stage m in terms of C and m ,

$$\frac{RC^m}{C-1}$$

with respect to C and equating the zero. Thus the optimum value of C varies from 2 with two stages and approaches 1 as a limit as the number of stages grows infinite.

Obviously many modifications and variations of the present invention are possible in the light of the above teachings. It is therefore to be understood that within the scope of the appended claims the invention may be practiced otherwise than as specifically described.

The invention described herein may be manufactured and used by and for the Government of the United States of America for governmental purposes without the payment of any royalties thereon or therefor.

I claim:

1. A cascade network comprising a plurality of variable function resistors each having a maximum value C times that of the preceding one, C being any finite constant greater than one, and being capable of variation from one function resistor to the next, a plurality of associated compensating resistors, a shiftable tie between each variable resistor and its associated compensating resistor such that as the variable resistor varies from a minimum to the said maximum value by equalling $(1-X)$ times the maximum value, X being proportional to the function to be measured by the resistor and varying from 1 to 0, the compensating resistor varies from a maximum to a minimum by equalling

$$\frac{CX}{C-X}$$

times the maximum value of the function resistor, means connecting the tie of each set of function and compensating resistors in series with the next function resistor, a final resistor having a value C times the maximum value of the last variable function resistor, means connecting the final resistor in series with the tie associated with the last variable resistor, and means connecting the final resistor and the compensating resistances in parallel with one another.

2. The cascade network specified in claim 1, the constant C being equal to 2.

3. A cascade computer network comprising a plurality of function resistors, a source of electrical supply, the resistors differing from each other by a constant factor, a compensating resistor for each function resistor, a shiftable connector between each function resistor and its compensating resistor, the first function resistor being connected at one end to the source of supply, each connector except the last one having a conductor ex-

tending to the next function resistor of next higher value and connecting them in series, each pair of function and compensating resistors being connected in parallel with the other pairs to the source of supply, the resistance of the function resistor increasing and that of its compensating resistor diminishing as its connector is shifted from one end to the other, and a load resistor connected by the conductor from the last connector also connected in parallel with the pairs of resistors to the source of supply.

4. An assembly of resistors for use in computers comprising a plurality of stages of resistor networks in cascade arrangement, each stage including a series arrangement of two variable resistors across the input thereto, one resistor variable to represent the variation of a predetermined mathematical function, the other resistor variable with said one resistor but in an opposite direction thereto, so that the sum total of the function resistor plus the net resistance of parallel combination of the said other resistance and the load presented by the stages following same is constant for any setting of the resistors, means coupling the said other resistor across the input of the succeeding stage, the net stage being greater than the preceding stage.

5. A plurality of resistor network stages in cascade arrangement wherein each stage includes a variable function resistor providing a resistance variation representing a mathematical function, a variable compensating resistor connected in series with said function resistor across the input to the stage, said compensating resistor wound so that the sum total of the resistance contributed by the function resistor of the stage at any setting thereof plus the net resistance of the compensating resistance in parallel with the load of all of the succeeding stages equals the maximum value of the function resistor of the stage, the values of the function resistors of each stage progressively increasing in value.

6. An assembly of resistors for use in computers comprising a plurality of stages of resistor networks in cascade arrangement; each stage including a series arrangement of two variable resistors across the input thereto; one of the resistors variable to represent the variation of a predetermined mathematical function, the other resistor variable with said one resistor but in an opposite direction thereto, so that the sum total of the function resistors plus the net resistance of parallel combination of the said other resistance and the load presented by the stages following them is equal to the maximum value of the function resistor of that stage, means coupling the said other resistor across the input of the succeeding stage, the said other resistor having a maximum value such that the parallel combination of this resistor and the function resistor of the next stage is equal to the maximum value of the function resistor of the stage, the value of the function resistor of each stage being greater than the function resistance of the previous stage.

7. A plurality of resistor network stages in cascade arrangement wherein each stage includes a variable func-

tion resistor providing a resistance variation representing a mathematical function, a variable compensating resistor connected in series with said function resistor across the input to the stage, means coupling the compensating resistor of each stage to the input of the succeeding stage, the function resistor of each stage being greater than the function resistor of the preceding stage, means varying said function and compensating resistors in opposite directions such that as the function resistor varies from a minimum to a maximum value by equaling $1-X$ times the maximum value thereof, X being proportional to the function indicated by the resistor and variable from 1 to 0, the compensating resistor varies from a maximum to a minimum by equaling

$$\frac{CX}{C-X}$$

times the maximum value of the function resistor of the stage where C is any number greater than 1 and is the ratio of the maximum value of the function resistor of the next stage to that of the function resistor of the stage, means coupling the compensating resistor of one stage to the input of the next succeeding stage.

8. The combination of claim 7 characterized further by a fixed load resistor coupled across the compensating resistor of the last stage and exceeding in value of the function resistor of the last stage, the net parallel resistance of the maximum value of the compensating resistance of the last stage and the said load resistor equalling the maximum value of the function resistor of the last stage.

9. The combination of claim 8 characterized further by "C" being equal to 2.

10. The combination of claim 7 characterized further by said coupling means providing an output contact movable over the variable function resistor, and the variable compensating resistor to provide a compensated output having a load impedance equal to a times that of the input impedance in which the compensating resistor satisfies the following relation:

$$R_{ci} = \frac{aR_1}{(a-1)}$$

in which R_{ci} is the compensating resistor for the first stage; R_1 is the impedance in the first stage of the circuit; and a is a constant having a value greater than one.
